FIG. 1

FIG. 2

FIG. 3

FIG. 4

FIG. 5

FIG. 6

FIG. 7

FIGURE 1 is a perspective view of an underwater face mask, showing my new design;

FIGURE 2 is a side view thereof;

FIGURE 3 is a bottom view thereof;

FIGURE 4 is a top view thereof;

FIGURE 5 is a fragmentary side elevation of a modified form of the mask shown in FIGURE 1, the difference residing in the inclusion of a one-way exhaust valve located near the front lower portion of said mask;

FIGURE 6 is a fragmentary side elevation of a further modified form of the mask shown in FIGURE 1, the difference residing in the inclusion of a one-way exhaust valve located at the bottom portion of said mask; and

FIGURE 7 is a view of the face of the one-way exhaust valve shown in FIGURES 5 and 6.

This application is a continuation-in-part of my application Serial No. D. 79,205, filed March 26, 1964, and now abandoned.

I claim:

The ornamental design for an underwater face mask, substantially as shown and described.
